FUSE CONSTRUCTION

William O. Schultz, South Milwaukee, Wis., assignor to McGraw Electric Company, a corporation of Delaware

Application February 21, 1948, Serial No. 10,040

5 Claims. (Cl. 200—121)

1

This invention relates to fuse constructions. Objects of this invention are to provide a fuse construction in which a transparent discolorable member, such for instance, as a cylinder is arranged within a transparent container and surrounds a fuse link and is so arranged that when the fuse link blows, the discolorable member will indicate that the fuse link has blown and the fuse cartridge can, therefore, be discarded and a new one substituted therefor.

In greater detail, further objects are to provide a cartridge type of fuse in which a transparent outer cylinder is provided and within which a cylinder of clear acrylic plastic such, for example, as that commonly known as "Lucite," is positioned and surrounds the fuse link and in which arc extinguishing material is located on opposite sides of the discolorable cylindrical member, such material being adapted to chill the arc and to provide a cooling and expansion chamber on each side of a gas evolving substance so as to permit the interruption of large currents at high voltage although the fuse construction constitutes merely a cartridge type of enclosed fuse of reasonable dimensions.

Further objects are to provide a construction in which a discolorable member is positioned and is arranged to indicate at all times the state of the fuse link, and in which means are provided for insuring the extinction of the arc and the chilling of any fulgurite or other semi-conducting fused section that may be formed in the chilling or cooling material so that the conducting quality of such path is quickly destroyed.

Further objects are to provide a cartridge type fuse in which means are provided for insuring the correct positioning and retention of the arc extinguishing material and of the discolorable member and of the fuse link itself and to provide such a construction as can be easily manufactured and assembled.

Embodiments of the invention are shown in the accompanying drawings, in which:

Figure 1 is a sectional view through a fuse construction showing one form that the invention may take.

Figure 2 is a sectional view on the line 2—2 of Figure 1.

Figure 3 is a sectional view on the line 3—3 of Figure 1.

Figure 4 is a detail of the barrier washer.

Figure 5 is a sectional view through one of the sealing rings.

Figure 6 is a perspective view of one of the end fittings for holding the central rod.

2

Figure 7 is a view corresponding to Figure 1 showing a further form of the invention.

Figure 8 is a sectional view on the line 8—8 of Figure 7.

Figure 9 is a sectional view on the line 9—9 of Figure 7.

Figure 10 is a perspective view of the indicating cylinder.

Referring to the first form of the invention, shown in Figures 1 through 6, it will be seen that the fuse construction comprises a transparent outer tubular casing 1 of glass or similar material having end caps 2 and 3 provided with terminal portions 4 and 5 and with locking screws or set screws 6, 6.

The end caps 2 are secured in place by means of a low melting point alloy 7 or any other suitable sealing compound, and preferably suitable gaskets 8 are interposed between the ends of the tubular member 1 and the end caps 2.

A ribbed or other shaped ceramic rod 9 is positioned centrally of the tubular transparent casing or housing 1 and is supported at its end by means of fittings 10 which are suitably slotted as indicated at 11, see Figure 6, and are provided with projecting stems or rods 12. These rods 12 are received in apertures 13 formed in the end caps 2 and 3 and are locked in place by means of the set screws or locking screws 6. If desired, the ends of the rods 12 and apertures 13 may be soldered over as indicated at 14 to seal the openings 13 after the rods 12 have been inserted and secured by the screws 6.

A fuse wire 15 is wound around the ceramic supporting rod 9 and is secured at its ends in any suitable manner to the fittings 10.

Centrally of the transparent tubular member 1 a cylindrical member 16 of a clear acrylic plastic, such as Lucite, is positioned. The cylindrical member 16 is provided with reduced portions 19 on which rubber washers 17 are positioned. These rubber washers 17 have thin flanges 18 which readily yield and accommodate any variation of the diameter of the tubular housing 1, as it has been found that due to manufacturing errors, the diameter of the members 1 vary. The purpose of the rubber washers 17 is to keep bauxite, hereinafter referred to, from sift ing into the space between the transparent cylindrical member 16 and the transparent housing 1.

The housing is filled with material in the following manner: As viewed in Figure 1 the housing or shell 1 is held vertically with the right hand end down and with the rod 9 and cylindrical member 16 properly held in place by means

not shown, and with the barrier washer 21 in place against the now upper end of the cylindrical member 16. The tube is filled above the washer 21 with powdered bauxite 20, the washer 21 preventing the bauxite from seeping through the opening 22 in the cylindrical member 16. Thereafter sand 23 is poured into the upper end of the housing 1 and a plaster of Paris seal 24 is formed to hold the granular or powdered material in place.

The housing is now inverted and bauxite 20 is poured into the other end of the housing, the bauxite filling the space 22 within the transparent cylinder 16 and filling the housing 1 to the point indicated in the drawings. Sand 23 is now poured into the housing and the plaster of Paris seal 24 is formed at the now upper end of the housing 1. The bauxite is preferably powdered, as stated, and the sand preferably a fine grained cutting sand.

The end caps 2 are secured in place after the housing 1 has been filled and the plaster of Paris seals 24 formed.

It is to be noted that the fuse link 15 is in close proximity to the surface of the aperture 22 of the transparent cylinder 16.

The clear acrylic plastic cylinder 16 has been found to have a peculiar action. When the fuse link blows it discolors the interior of the transparent plastic cylinder 16 and forms a distinctive pattern which is readily observable from the outside of the transparent casing or housing 1. Although a fuse link of considerable length is employed, it has been found that substantially uniformly, the blowing or rupturing of the fuse link occurs centrally of the fuse construction. It has been found also that due to the curvature or cylindrical formation of the plastic cylinder 16, a magnifying effect is produced which further enhances or augments the visibility or ease with which detection of a blown fuse may be had.

It is intended that the entire fuse cartridge shall be discarded after the fuse link has blown and a new cartridge substituted.

It has been found that when the fuse link blows, that the bauxite 20 releases a quantity of vapor, including water vapor, and this tends to chill or cool the arc. Further the sand 23 provides an expansion area for the gases generated by the blowing of the fuse link and provides a vast or extended surface to act as a cooling surface for the hot gases. Under certain conditions a fulgurite is formed in the sand upon the rupture of the fuse link. The water vapor liberated by the bauxite quickly chills this fulgurite and prevents it from reaching a temperature so high that it would become a conductor, support the arc and cause failure of the device.

It has been found that although the fuse construction is of a cartridge type, that nevertheless it is satisfactory for use in interrupting large currents at high voltage without generating an excessive gas pressure within the cartridge.

A further form of the invention is shown in Figures 7 through 10. In this form of the invention the outer tubular casing or housing indicated at 25 may be of fiber, Bakelite, or other suitable non-transparent material. One end of the outer tubular member 25 is provided with a fitting 26 with a flange which is centrally apertured as indicated at 27. A threaded metal member 28 extends through the aperture 27 and is provided with inwardly located flanges 29. It is provided with a hood or shield portion 30 which is cut out on its under side as shown most clearly in Figure 9. The threaded portion 28 receives a nut 31

5 which clamps one of the terminal members 32' in place. The hood-like member 30 extends downwardly and may have a curved outer end as indicated at 32. It houses a clear acrylic plastic cylindrical member 33 which is provided with a small central aperture 34. This cylindrical member 33 is visible from the cutaway portion 30, see Figure 9, of the hood-like part 30.

10 The other end of the tubular end of casing 25 is provided with a cup-shaped end fitting 35 of metal which is clamped in place by means of a screw 36 and nut 37 to a terminal member 38. The cup-shaped member 35 is held in place by a flanged ferrule or cylindrical member 39 which is screw threaded onto the casing 25. A ribbed, ceramic central member 40 is positioned within the outer tubular member 25 and one end is received in a tubular metal end piece 41 which is secured to a flexible braided conducting strip 42 and which is urged inwardly by means of a spring 43. The flexible tape or conducting member 42 is clamped between the end of the tubular member 25 and the conducting cup-shaped member 35. The spring 43 urges the ceramic rod 40 to the left as viewed in Figure 7 against an asbestos washer 44 which bears against a conically apertured fiber member 45. The fiber member 45, in turn, bears against the indicating transparent cylinder 33 hereinbefore described.

15 20 25 30 35 30 A fuse link 46 is wrapped around the ceramic supporting central member 40 as indicated and one end is secured to the metallic holding member 41 and the other end to a plug 47, which is received in an aperture 48 formed in the hood-like portion 32 of the member 30 and soldered in place as indicated at 49.

35 40 45 50 The central portion of the tubular member 25 is filled with powdered bauxite 50 and the end areas of the tubular member 25 are filled with sand 51. The sand 51 may be a fine grained, cutting sand as previously described, such as the sand used for sand blasting for instance.

On overload, particularly on relatively heavy overload, the fuse link 46 melts throughout its length and the action of the bauxite 50 and sand 51 is identically as previously described. The fusing of the fuse link 46 within the aperture 34 of the clear, acrylic plastic cylinder 33, such for instance as Lucite, gives the discoloration hereinbefore described and indicates that the fuse has blown.

55 60 65 70 75 The first form of the invention shown in Figures 1 through 6 is the preferred form, although the form shown in Figure 7 can be satisfactorily used as hereinabove described, and if the fuse link is of uniform cross-section throughout, it is primarily intended for relatively heavy overloads. On the other hand, it is within the province of this invention to form the section of the fuse link 46 of Figure 7 of a reduced cross-sectional area in the point where it passes through the cylinder 33 so as to insure rupture at this point as well as at other points along the length of the fuse link.

The first form of the invention is the preferred form for another reason. It has been found that when the fuse blows in either form of the invention, that there is discoloration of the clear acrylic plastic. However, it has been found that when bauxite is present within the clear acrylic plastic cylinder 16 in the first form of the invention as is shown in Figure 3, that there is an increase in the discoloration or, in other words, the discoloration is more pronounced.

75 It has been found that as the melting point of

the fuse link is approached, the polished inner surface of the plastic cylinder 16 melts and causes the bauxite to stick and possibly absorb some of the liquid plastic. This gives a very distinct discoloration which is more pronounced than if no bauxite is present.

The porcelain or other refractory supporting rod for the fuse link shown in both forms of the invention could be omitted for fuses arranged for lower voltages as the fuse link would be heavier and need not necessarily be supported. However, for higher voltages it is difficult to handle and control the fuse wire mechanically during the filling operation and for this reason the refractory supporting rod for the fuse link offers the simplest and best solution.

In both forms of the invention the cylindrical plastic discolorable indicating cylinder has somewhat of a magnifying effect and makes it easier to see that the interior surface has been discolored upon blowing of the fuse link.

It has been found that fuses constructed in accordance with this invention are capable of handling larger overloads without venting any of the gases to the outside and yet without subjecting the external casing to excessive internal pressure.

It will be seen further that the fuse constructions are of simple type and may be readily produced and assembled.

Although this invention has been described in considerable detail, it is to be understood that such description is intended as illustrative rather than limiting, as the invention may be variously embodied and is to be interpreted as claimed.

I claim:

1. A fuse construction comprising a tubular casing, terminals adjacent opposite ends thereof, a fuse link within said tubular casing and electrically connecting said terminals, and an acrylic plastic cylinder surrounding a portion of said fuse link and characterized by the fact that it will discolor upon rupture of said link, said construction including transparent means adjacent said plastic cylinder, said plastic cylinder being visible from the exterior of said casing.

2. A fuse construction comprising a transparent tubular outer casing, terminals adjacent opposite ends thereof, a fuse link electrically connecting said terminals and extending through said casing, and a clear acrylic plastic cylinder located within said casing and surrounding a portion of said fuse link and characterized by the fact that it discolors upon rupture of said fuse link.

3. A fuse construction comprising a transpar-

ent tubular outer casing, terminals adjacent opposite ends thereof, a clear acrylic plastic cylinder within said casing and visible through said casing, a fuse link electrically connecting said terminals and located within said casing and having an intermediate portion extending through said cylinder, powdered bauxite within said casing and located on opposite sides of said cylinder, and sand within said casing located on opposite sides of said bauxite.

4. A fuse construction comprising a transparent tubular outer casing, terminals adjacent opposite ends thereof, a clear acrylic plastic cylinder within said casing and visible through said casing, yielding washers surrounding end portions of said cylinder and wedging against the interior surface of said casing, a fuse link electrically connecting said terminals and located within said casing and having an intermediate portion extending through said cylinder, powdered bauxite within said casing and located on opposite sides of said cylinder, and sand within said casing located on opposite sides of said bauxite.

5. A fuse construction comprising a transparent tubular outer casing, terminals adjacent opposite ends thereof, a clear acrylic plastic cylinder within said casing and visible through said casing, a fuse link electrically connecting said terminals and located within said casing and having an intermediate portion extending through said cylinder, powdered bauxite within said casing and having portions located on opposite sides of said cylinder and having a portion located within said cylinder, and sand within said casing located on opposite sides of said bauxite.
